UNITED STATES PATENT OFFICE.

THOMAS E. RICH AND CHARLES T. RICH, OF BARRE PLAINS, MASSACHUSETTS.

MACHINE FOR JOINTING BARS OF WINDOW-SASHES.

SPECIFICATION forming part of Letters Patent No. 595,077, dated December 7, 1897.

Application filed February 9, 1897. Serial No. 622,710. (No model.)

To all whom it may concern:

Be it known that we, THOMAS E. RICH and CHARLES T. RICH, citizens of the United States, residing at Barre Plains, in the town 5 of Barre, county of Worcester, and State of Massachusetts, have invented a new and useful Improvement in a Machine for Jointing the Bars of Window-Sashes, of which the following is a specification, reference being had

to the accompanying drawings, forming a part of the same, in which—

Figure 1 represents a front view of a machine embodying our invention. Fig. 2 is a side view of the same. Fig. 3 is a vertical 15 central sectional view on line 3 3, Fig. 1. Fig. 4 represents one of the detachable bed-pieces which is attached to the tilting table on which the work is supported, and Fig. 5 represents a window-sash having diamond-shaped panes 20 and requiring the bars of the sash to be placed at an angle to each other other than a right angle.

Similar letters refer to similar parts of the different figures.

25 The object of our present invention is to provide a machine for cutting the ends of sash-bars at an acute angle, such as are required in building sash for diamond-shaped panes, as represented in Fig. 5, and our invention 30 consists in the construction and arrangement of parts, as hereinafter described, and pointed out in the annexed claims.

Referring to the accompanying drawings, A denotes an upright stand on which the operating parts of the machine are supported.

35 B denotes a sliding head sliding in ways B' on the front of the stand A and carrying a pair of cutting-knives B² and B³.

The sliding head B is operated by a bell-40 crank lever C, pivoted in the upper portion of the stand A and arranged to carry the sliding head downward by a foot-treadle C' and connecting-rod C² and upward by the blade-spring C³ and link C⁴, the above-enumerated parts being similar in their construction 45 and operation to the corresponding parts in foot mortising-machines such as are now in common use.

In front of the stand A is a plate D, attached at its lower edge to a spindle D', which is capable of sliding in the stand A and is

held in position by a set-screw D². The stand A is provided with a screw-threaded hole E to receive a screw E', having a hand-wheel E² at one end and a neck E³ at the opposite end, 55 journaled in the plate D, so that by loosening the set-screw D² and by rotating the screw E' the plate D can be moved away from or toward the upright stand A. Pivoted at F upon the front side of the plate D are bars which 60 form tables F' and F², by which the work is supported. The plate D is provided with curved slots F³, concentric with the pivots F, to receive tightening-screws F⁴, which are screwed into the tables F' F² and serve to 65 hold them at the desired angle. The tables F' F² are provided with longitudinal slots F⁵ to receive the tightening-screws F⁶, which screw into the wooden bars G G, forming the bed-pieces upon which the work rests. 70

The upper faces of the bed-pieces C are channeled, as at G', Fig. 2, to accurately fit the molded side of a sash-bar.

The tables F' and F² are placed at the proper angle to a vertical plane, and the bed-pieces 75 G G are moved downwardly upon the tables until the corners of their lower ends intersect the path of the knives, so that on the downward movement of the sliding head B the knives B² and B³ will cut the corners of the 80 bed-pieces on the lines G² G³. The sash-bar to be cut is then laid upon one of the bed-pieces G in the proper position to have the lower end shaved off by one of the downwardly-descending knives and trimmed at an 85 angle corresponding to the angular position of the table which supports the sash-bar.

During the cutting operation the bed-pieces G G form a solid support for the under side of the sash-bars to the cutting-line of the descending knives, as the downward path of the cutting edges of the knives B² and B³ coincides with the lines G² G³. The support of the under side of the sash-bar up to the cutting-line of the knives is necessary in order 90 to prevent the splintering of the bar upon the under side as the knife passes through it. Whenever the angle of the tables is changed in order to cut the sash-bars at a different angle, the bed-pieces G are moved so as to be 95 again trimmed by the knives B² B³, so that the beveled ends of the bed-pieces will always 100

correspond with the path of the cutting edges of the knives. The sash-bar support is therefore capable of three separate and independent adjustments: first, by the movement of the plate D toward or away from the stand A; second, by the adjustment of the angle of the pivoted tables F' and F², and, third, by the longitudinal movement of the bed-pieces G G, by which their lower ends are brought under the knives B² and B³, so as to bevel the ends of the bed-pieces on a line coinciding with the path of the cutting edges of the knives B² and B³.

We do not claim as new any of the operating mechanism by which the knives are moved downwardly, neither do we claim as broadly new the provision of an adjustable work-support; but in our improved machine we provide special adjustments which adapt it to the special work it is intended to perform, and we also provide means for the solid support of the sash-bar immediately next to the cutting-line whatever the angle of the tables may be, whereby we prevent the splintering of the fibers of the wood on its lower side by the edges of the cutting-knives.

By the above-described apparatus the end of the sash-bar is cut smoothly without the splintering of the wood, and the angle at which the end is cut is readily changed, and the absolute control of the work relatively to the path of the cutting edges of the knives B² and B³ is secured. The table for supporting the work is pivoted at its lower end and at one side of the path of the descending knife, so that the angular adjustment of the table varies the lower end but little relatively to the path of the knife and allows the work to be moved downwardly into the path of the knife.

What we claim as our invention, and desire to secure by Letters Patent, is—

1. An organized machine for jointing the bars of window-sash and comprising in combination the following instrumentalities a supporting-frame provided with ways for a reciprocating knife, a vertically-reciprocating knife, a vertical plate held by said frame and

horizontally adjustable whereby the face of said plate is carried toward or away from the path of said knife, a table having one edge resting against the face of said plate and pivoted at one end to said plate, means for holding said table at an oblique angle to the path of the knife, a wooden bed-piece lying on the upper side of said table, means for adjusting said bed-piece longitudinally whereby its end is carried into the path of the reciprocating knife, and means for imparting a vertically-reciprocating motion to said knife, substantially as described. 60

2. In a machine for jointing sash-bars, the combination of an upright stand provided with vertical ways for a reciprocating knife, a reciprocating knife, a spindle held in said stand and adjustable in a horizontal plane, a vertical plate attached to said spindle, a table pivoted at one end upon the front side of said vertical plate, means for holding said table at an oblique angle to the path of said knife, a wooden bed-piece held on said table and longitudinally adjustable thereon, and means for reciprocating said knife past said wooden bed-piece, substantially as described. 70

3. The combination of the upright stand A provided with ways for a reciprocating knife, a spindle D' held in said stand, a vertical plate D attached to said spindle and located behind the path of said knife, means for moving said plate toward or away from the path of the knife, a table F' pivoted at one end to said plate, means for holding the opposite end of said table in a fixed position, said table having a longitudinal slot, a wooden bed-piece resting on said table, bolts held in said bed-piece and extending through said slot and tightening-nuts carried by said bolts and means for reciprocating said knife past said wooden bed-piece, substantially as described. 80 85

Dated this 30th day of January, 1897.
